US00D960211S

(12) **United States Design Patent** (10) **Patent No.:** **US D960,211 S**
Suchman et al. (45) **Date of Patent:** **** Aug. 9, 2022**

(54) **DEBRIS CONTAINER**

(71) Applicant: **iRobot Corporation**, Bedford, MA (US)

(72) Inventors: **Jason Jeffrey Suchman**, Arlington, MA (US); **Douglas Dell'Accio**, Boston, MA (US); **Andrew Vincent Wolff**, Norfolk, MA (US); **Flavia Pastore**, Wakefield, MA (US)

(73) Assignee: **iRobot Corporation**, Bedford, MA (US)

(**) Term: **15 Years**

(21) Appl. No.: **29/811,496**

(22) Filed: **Oct. 14, 2021**

Related U.S. Application Data

(63) Continuation of application No. 29/741,453, filed on Jul. 13, 2020, now Pat. No. Des. 934,314, which is a continuation of application No. 29/646,577, filed on May 4, 2018, now Pat. No. Des. 890,231.

(51) **LOC (13) Cl.** **15-09**

(52) **U.S. Cl.** **USPC** **D15/122**

(57) **CLAIM**

The ornamental design for a debris container, substantially as shown and described.

DESCRIPTION

FIG. 1 is a perspective view of the debris container.

FIG. 2 is a front view thereof.

FIG. 3 is a back view thereof.

FIG. 4 is right side view thereof.

FIG. 5 is left side view thereof.

FIG. 6 is top view thereof; and,

FIG. 7 is bottom view thereof.

The broken lines illustrate environmental features that form no part of the claimed design.

1 Claim, 7 Drawing Sheets
